Gerardine Mueller, Caldwell, N. J.

Application July 25, 1950, Serial No. 11,390

Term of patent 14 years

(Cl. D64—12)

To all whom it may concern:

Be it known that I, Gerardine Mueller, a citizen of the United States of America, residing at Caldwell, New Jersey, in the county of Essex and State of New Jersey, have invented a new, original, and ornamental Design for an Alphabet for Forming Monograms or the like, of which the following is a specification, reference being had to the accompanying drawing, forming part thereof.

The drawing illustrates an alphabet for forming monograms or the like, showing my new design.

I claim:

The ornamental design for an alphabet for forming monograms or the like, substantially as shown.

GERARDINE MUELLER.
